UNITED STATES PATENT OFFICE.

CLARENCE A. KESSLER, OF CHICAGO, ILLINOIS, ASSIGNOR TO C. L. WILLEY COMPANY,
OF CHICAGO, ILLINOIS, A CORPORATION OF ILLINOIS.

VENEER MACHINE.

Application filed April 27, 1928. Serial No. 273,277.

This invention relates to improvements in veneer machines, and more especially to the chuck and stay log of such a machine.

One of the features of my invention is the provision of a rigid, stiff, stay log that does not bow or yield during the cutting operation.

Another feature of my invention is the provision of improved chucks permitting quick and easy adjustment of the log with respect to the knife.

Other features and advantages of my invention will appear more fully as I proceed with my specification.

In that form of device embodying the features of my invention shown in the accompanying drawings, Fig. 1 is a view in front elevation, Fig. 2 is a view taken on the line 2 of Fig. 1, Fig. 3 is a view taken on the line 3 of Fig. 1, Fig. 4 is a view taken on the line 4 of Fig. 2, Fig. 5 is a vertical sectional view of a chuck and bracket, Fig. 6 is a view taken as indicated by the line 6 of Fig. 1, Fig. 7 is a broken plan view of one of the brackets, and Fig. 8 is a view taken on the line 8 of Fig. 1.

As shown in the drawings, 10 indicates in general an ordinary type of veneer machine to which my inventions may be applied. Such machines, in general, are old in the art and consequently it will not be necessary to describe one here, except as may be necessary to explain my inventions. Such a machine resembles, to a certain extent, a lathe and is provided with the usual rotatable chuck spindles 11 and 12 which are adjustable toward and away from each other to accommodate logs of different lengths. 13 indicates the knife which cuts the sheets of veneer from the log as it is rotated.

Each spindle carries a chuck 14 which in turn carries a bracket 15 to support one end of the stay log 16. The bracket 15 includes the end piece 15^a and supporting piece 15^b. Since the chuck and bracket at each end of the machine are the same, I shall describe but one.

The face of the chuck 14 is provided with teeth to engage the end of the log 18. These teeth comprise circular projecting members 17 each having a concave depression 19 at its end. I have found that teeth of this form give a very firm grip on the log with practically no tendency to split the same.

The bracket 15 is adjustably mounted on the chuck so that logs of different thicknesses

may be accommodated and so that the proper adjustment toward and away from the knife may be accomplished as the cutting progresses. The sheets of veneer 20 are cut from the log eccentrically, as shown in Fig. 6, and when one side has been cut near enough toward the center the log is turned over.

The adjustment of the bracket 15 is provided for as follows: The face of the chuck 14 has two keyholes or undercut parallel slots 21 lying at each side of the center. Outside of these slots and parallel therewith are two guide ribs 22 between which the end piece 15^a of the bracket 15 may slide as it is adjusted. The bracket 15 is held firmly in its adjusted positions by two bolts 23 passing through the end piece 15^a with their squared heads 23^a lying in the slots 21. 23^b indicates a nut on each bolt 23, which, when tightened, holds the bracket firmly against the face of the chuck. The bracket 15 is adjusted or slid between the guide members 22 by means of a screw 24 threaded into the end piece 15^a and passing through a lug 25 on the face of the chuck.

The screw 25 is provided with a collar 24^a resting on the lug 25. It is to be understood that the nuts 23^b are loosened before the bracket is adjusted and then tightened to hold the same firmly in position. The supporting plate 15^b of each bracket is provided with slots 15^c to accommodate bolts 26 for fastening the stay log and to permit adjustment of the brackets toward and away from each other. This plate is also preferably provided at its edges with raised flanges 15^d between which the end of the stay log lies.

The stay log, indicated in general by 16, comprises an I-beam 16^a having attached to it a channel 16^b above and a plate 16^c below. The channel is somewhat narrower than the I-beam and blocks 16^d are placed between the flanges thereof and held in place in any suitable manner, as by welding. The plate 16^c is just wide enough to lie on the supporting plate 15^b of the bracket 15 between the flanges 15^d.

The log 18 rests on the channel 16^b of the stay log and its ends are gripped by the teeth 17 on the chucks. The log is additionally held by one or more lag screws 27 passing through the stay log, midway of its edges.

While I have shown and described certain embodiments of my invention, it is to be understood that it is capable of many modifications. Changes, therefore, in the construction and arrangement may be made without

departing from the spirit and scope of the invention as disclosed in the appended claims, in which it is my intention to claim all novelty inherent in my invention as broadly as possible in view of the prior art.

What I claim as new, and desire to secure by Letters Patent, is:

- 5 1. In a veneer machine of the character described; a stay log including an I-beam with a log supporting channel on the upper side thereof.
- 10 2. In a veneer machine of the character described; a bracket having a supporting plate with raised flanges at its edges; and a stay log comprising an I-beam with a plate on the underside thereof, the end of said plate adapted to rest on the supporting plate of the bracket and fit snugly between the raised flanges at the edges thereof.
- 15 3. In combination with a stay log as claimed in claim 1, a lag screw projecting through said stay log, midway of its edges, and adapted to project into a log supported on said stay log.
- 20 4. In combination with mechanism as

claimed in claim 2, a lag screw projecting through the stay log, midway of its edges, and adapted to project into a log supported on the stay log.

5. In a veneer machine of the character described; a chuck having its face provided with an undercut slot; a bracket radially adjustable on the chuck, having an end piece lying against the face of the chuck and a plate adapted to support the end of a stay log; a bolt passing through the end piece of the bracket with its head lying in the slot in the face of the chuck and adapted to be tightened to hold the bracket tightly against the face of the chuck in its adjusted position; two parallel guide ribs on the face of the chuck adjacent the sides of the end piece of the bracket; and means for radially adjusting the bracket on the chuck, said bracket adapted to slide between said guide ribs while being adjusted.

In witness whereof, I have hereunto set my hand this 24th day of April, 1928.

CLARENCE A. KESSLER.
